(57) **CLAIM**

The ornamental design for a heat and CO detector, as shown and described.

DESCRIPTION

1. Heat and CO detector

1.1 : Perspective

1.2 : Front

1.3 : Back

1.4 : Top

1.5 : Bottom

1.6 : Left

1.7 : Right

Reproduction 1.1 is a perspective view; reproduction 1.2 is a front view; reproduction 1.3 is a back view; reproduction 1.4 is a top view; reproduction 1.5 is a bottom view; reproduction 1.6 is a left view; reproduction 1.7 is a right view; the reflections shown in reproductions 1.4-1.7 are disclaimed.
